WILLIAM L. NANCOLAS, OF MODESTO, CALIFORNIA.

HAIR-WAVING IMPLEMENT.

Application filed May 10, 1927. Serial No. 190,204.

This invention relates to hair curling irons, my principal object being to provide an implement for the purpose by means of which artificial waves may be made in the hair by any person without the experience and skill heretofore necessary in performing this operation.

By means of my improved iron therefore women can have their hair waved in their own homes by a member of the family or other person, without the inconvenience frequently attending a visit to a specialist and without having to pay for the operation.

While my iron is especially designed for home use it will be equally valuable in the hands of professionals since it will enable their work to be speeded up, facilitated and rendered more certain.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

30 Fig. 1 is a side elevation of my curling iron showing the jaws in their closed positions.

Fig. 2 is a similar view with the jaws open or spread.

35 Fig. 3 is an enlarged fragmentary longitudinal section of the device.

Fig. 4 is an enlarged cross section on the line 4—4 of Fig. 1.

Referring now more particularly to the characters of reference on the drawings, the numerals 1 and 2 denote a pair of operating handles of suitable dimensions pivoted together at one end as at 3 and having rigid jaw supporting bars 4 and 5 respectively projecting beyond the pivot and arranged in spaced and parallel relation to each other when the handles are brought together.

Fixed on the bars are lower and upper hair engaging jaw units comprising male and female members 6 and 7 respectively, extending lengthwise of the bars and channel shaped in cross section. The sides of the members 6 are both formed of a row of long narrow and closely spaced teeth 8.

55 One side of the member 7 is formed as a

solid plate, while the other side has a number of relatively short and widely spaced teeth 9. The lower edge of the solid side member of the jaw 7 has an outwardly and downwardly angled lip 10, arranged to cooperate with a similarly disposed lip 11 projecting from the adjacent outer end of the jaw 6, just beyond the base of the teeth 8 thereon.

Slidable on the jaw member 6 at the bottom and inwardly thereof is a channel shaped slide 12, whose sides are formed as rows of narrow teeth 13 spaced transversely from the teeth 8 and practically the same height as said teeth. The slide is held in place by suitable means such as longitudinally spaced straps 14 projecting through slots in the adjacent jaw member and engaging the bar 4. The slide is manipulated at will by the person grasping the handles by any suitable means such as a finger trigger or pad 15 disposed alongside the implement, preferably adjacent the pivot 3 and connected to the adjacent end of the slide by a suitably bent rigid rod 16.

Mounted in connection with the jaw 7 inwardly of the same is an electric heating element 17 which is enclosed in a longitudinally extending housing 18, which when the jaws are closed depends between the teeth 13 of the slide in transverse clearance relation therewith. The current conducting cable 19 of the element preferably extends inside the corresponding handle to the outer end of the same to form a flexible extension cord for connection to a convenient outlet or light socket.

Disposed between the adjacent rows of teeth 13 and 8 are longitudinal bars 20 which are connected to the bar 4 by pivoted links 21 in the ends of said bars. Pivotedly connected to the bars 20 at the handle end thereof and in common with the pivotal connection of the adjacent links 21 therewith are links 22, the opposite ends of which are pivoted onto the opposite bar 5. The arrangement of the links 22 is such that when the handles are closed and the jaws are adjacent each other, the bars 20 will be disposed at the bottom of the jaw 6. As the handles are opened and the jaws are spread apart the bars will be raised from the jaws until they move above the points of the teeth 8 and 13, as shown in Fig. 2.

In operation the operator grasps the

handles and opens the jaws, holding the implement so that the lips 10 and 11 are toward the head. The amount of hair to be treated at one operation is then held away from the head and the tool manipulated so that this hair will pass between the jaws, resting temporarily on the bars 20 which are then raised. The jaws are then closed snugly so that the hair will be pinched or clamped 10 between the lips 10 and 11, while freely passing between the teeth of the various rows. With the closing of the jaws the housing of the heating element comes in contact with the hair confined between the jaws, as will be 15 evident, and imparts the necessary heat to the hair.

The hair will then have a slight wave imparted thereto in a vertical transverse plane owing to the offset alinement of the clamping lips, the top of the release bars 20 and the bottom face of the element housing. Up to this time the slide is not disturbed but as soon as the jaws are firmly closed as above described, the finger pad 15 is engaged by the 25 thumb or finger so as to draw the slide along. Since the hair is disposed between and engaged by the movable slide teeth and the relatively stationary jaw teeth as well, this movement of the slide causes the hair to be 30 drawn longitudinally of the implement into a transverse horizontal wave between the stationary jaw teeth. If the slide is left in this position for some time and the jaws are likewise held closed, the hair will retain the 35 waved formation into which it has been thus drawn. When moving the slide no pull on the hair is imparted to the head, since the lips 10 and 11 hold the hair clamped against movement adjacent the head, while at the 40 same time said hair is free to slide between the teeth on the opposite side of the implement.

When the jaws are again opened the bars automatically raise as before described and 45 clear the hair from the teeth. The implement may be then readily disassociated from the hair without danger of the latter becoming entangled in the teeth or being pulled and without disturbing the formed wave. 50 The member 15 is then released, whereupon the slide will automatically return to its original position, due to the action of a spring 12^a connected to the bar 4 and one of the straps 14. The implement is then ready 55 for the next curling operation.

From the foregoing description it will be readily seen that I have produced such a device as substantially fulfills the objects of the invention as set forth herein.

60 While this specification sets forth in detail the present and preferred construction of the device, still in practice such deviations from such detail may be resorted to as do not form a departure from the spirit of the 65 invention, as defined by the appended claims.

Having thus described my invention, what I claim as new and useful and desire to secure by Letters Patent is:

1. A hair-waving implement comprising opposed jaws between which the hair to be 70 waved is placed transversely, heating means for the hair mounted in connection with one jaw, means for clamping the hair along one side of the jaws, means on the other side of the jaws preventing movement of the hair 75 longitudinally of the implement while permitting free sliding movement of the hair transversely of the jaws, and means for drawing the hair lengthwise in the implement between the sides of the jaws. 80

2. A hair-waving implement comprising opposed jaws between which the hair to be waved is placed transversely, heating means for the hair mounted in connection with one jaw, cooperating clamping lips along the 85 jaws at one side and between which the hair passes, cooperating upstanding teeth along the opposite side of the jaws between which the hair also passes, and means for drawing the hair longitudinally of the jaws between 90 said teeth and the clamping lips.

3. A hair-waving implement comprising opposed jaws between which the hair to be waved is placed transversely, heating means for the hair mounted in connection with one jaw, means for drawing the hair lengthwise 95 of the implement to form a wave therein intermediate the opposite sides of the jaws, upstanding teeth provided with the jaws and between which the hair is disposed when the 100 jaws are closed, bars on which the hair rests arranged in connection with the jaws lengthwise thereof, links pivoting the bars at one end onto one jaw, and link means between the other end of the bars and the jaws arranged to cause said bars to lie adjacent the base of the teeth when the jaws are closed, and to be moved so that the hair supporting 105 surface of the bars lies outwardly of the points of the teeth when the jaws are spread. 110

4. A hair waving implement including a pair of opposed jaws, male and female jaw units; the male unit comprising a longitudinal element and teeth along the sides thereof projecting toward the female jaw 115 unit; and the female unit comprising a longitudinal element, teeth along one side thereof disposed outwardly of the corresponding row of teeth of the male unit, and a plate along the other side of the last named element disposed outwardly of the other row of teeth of the male unit; hair clamping lips along the adjacent edges of said plate and first named unit, and a heating device mounted on said last named element and 120 projecting toward the other element in the space between the rows of teeth of the male unit in spaced relation to said teeth.

5. A hair waving implement including a pair of opposed jaws, male and female jaw 125

units; the male unit comprising a longitudinal element and teeth along the sides thereof projecting toward the female jaw; and the female unit comprising a longitudinal element, teeth along one side thereof disposed outwardly of the corresponding row of teeth of the male unit, and a plate along the other side of the last named element disposed outwardly of the other row 10 of teeth of the male unit; hair clamping lips along the adjacent edges of said plate and first named unit, the hair being arranged to extend transversely of the jaws between the teeth and the lips, and a slide mounted on 15 one unit for longitudinal movement relative thereto and having teeth along the sides thereof disposed inwardly of the rows of teeth of the male unit.

6. A structure as in claim 5, with bars

disposed between the adjacent sets of teeth 20 of the slide and male jaw unit, and means connecting the bars to the jaw units to cause said bars to lie adjacent the base of the teeth when the jaws are closed and to be moved to the points of the teeth when the jaws are 25 spread.

7. A hair waving implement including opposed jaws between which the hair to be waved is placed transversely, cooperating and opposed teeth along the jaws at one 30 side thereof, and clamping lips between the jaws along the opposite sides thereof.

8. A structure as in claim 7, with means disposed between said lips and teeth for drawing the adjacent portion of the hair 35 lengthwise of the implement.

In testimony whereof I affix my signature.

WILLIAM L. NANCOLAS.
